PROCESS FOR THE PRODUCTION OF AZO
DYESTUFFS ON THE FIBER

Heinrich Morschel and Ludwig Nüssler, Leverkusen, Rhine, and Hans Krzikalla and Wolfgang Alt, Ludwigshafen, Rhine, Germany, assignors to General Aniline & Film Corporation, a corporation of Delaware

No Drawing. Application March 7, 1939, Serial No. 260,338. In Germany March 14, 1938

10 Claims. (Cl. 8—22)

The present invention relates to a process of dyeing mixtures of wool and cellulosic fibers and to fibers dyed according to this process.

It has been found that mixtures of wool and cellulosic fibers can be uniformly dyed by applying to these mixtures arylamides of 6-sulfo-2-hydroxynaphthalene-3-carboxylic acid, which are derived from aromatic diamines or polycyclic monoamines and developing them to azo dyestuffs with diazo compounds of aromatic amines on the fibers thus pre-treated.

Arylamides of the mentioned type are condensation products of 6-sulfo-2-hydroxynaphthalene-3-carboxylic acid with, for instance, di-amino compounds of benzene and mono- and diamines of diphenyl, diphenylether, diphenylamine, naphthalene, fluorene, carbazole, diphenyleneoxide, benzothiazole and so on.

These arylamides of 6-sulfo-2-hydroxynaphthalene-3-carboxylic acid are easily soluble in aqueous solutions of weak alkalis, for instance, of alkali metal carbonates, ammonia and similar compounds. The arylamides go from these solutions uniformly on wool and regenerated cellulose. On account of the weak alkalinity of the solutions practically no damage is done to the animal fiber of the mixture. The development of dyestuffs on the fiber with diazotized aromatic amines is carried out in the usual way. By this process dyeings of even shades ranging from orange to black are obtained which are distinguished in general by good fastness to water, rubbing and light.

The following examples illustrate the invention without, however, restricting it thereto.

Example 1

10 g. of a mixed fabric consisting of 70% of wool and 30% of staple fiber are treated for one hour at 75—80° C., if desired, in the presence of a wetting agent, in a grounding bath, which contains per liter 4 g. of 4,4'-di(6'-sulfo-2'-hydroxynaphthalene-3'-carboxylamino)-diphenyl (dissolved at the boil with 0.3 part of sodium carbonate per 1 part "naphthol") and 20 g. of sodium sulfate (bath ratio 1:20). After grounding the material is squeezed and developed in the cold for 45 minutes with a diazo solution prepared from 2,5-dichloroaniline.

The developed dyeing is aftertreated for half an hour at 80—90° C. in the presence of a neutral dispersing or washing agent. A yellowish red of good fastness properties is obtained.

Example 2

10 g. of a mixed yarn consisting of 70% of wool and 30% of staple fiber are grounded for an hour at 75—80° C., if desired in the presence of a wetting agent in a bath which contains per liter 5 g. of 4-(6'-sulfo-2'-hydroxynaphthalene-3'-carboxylamino)-diphenyl (dissolved with addition of sodium carbonate) and 20 g. of sodium sulfate (bath ratio 1:20). Then the yarn is squeezed and developed for 45 minutes in the cold with a diazo solution prepared from 1-methyl-2-amino-5-chlorobenzene. The aftertreatment is the same as described in Example 1. A red of good fastness properties is obtained.

In the following table further dyeings obtainable in the same way are arranged.

Azo component	Diazo component	Shade
4,4'-di(6'-sulfo-2'-hydroxynaphthalene-3'-carboxylamino)-diphenyl.	1-amino-3-chlorobenzene.	Strongly yellowish red. 40
Do.	1-methyl-2-amino-4-chlorobenzene.	Do.
Do.	1-methyl-2-amino-5-chlorobenzene.	Yellowish red.
Do.	2-amino-4-chlorodiphenylether.	Do.
3,3'-dimethoxy-4,4'-di(6'-sulfo-2'-hydroxynaphthalene-3'-carboxylamino)-diphenyl.	1-methyl-2-amino-4-chlorobenzene.	Strongly reddish brown.
Do.	1-amino-2-chlorobenzene.	Reddish brown.
Do.	1-methyl-2-amino-5-nitrobenzene.	Full red brown.
Do.	4-amino-4'-methoxy-diphenylamine.	Black.
Do.	do.	Do.
45 1,5-di(6'-sulfo-2'-hydroxynaphthalene-3'-carboxylamino)-naphthalene.	1-methoxy-2-amino-4-chlorobenzene.	Reddish Bordeaux.
4,4-di(6'-sulfo-2'-hydroxynaphthalene-3'-carboxylamino)-benzene.	1-methoxy-2-amino-5-nitrobenzene.	Brownish red bordeaux.
Do.	4-amino-4'-methoxy-diphenylamine.	Black.
Do.	1-amino-2-chlorobenzene.	Scarlet.
50 2-(6'-sulfo-2'-hydroxynaphthalene-3'-carboxylamino)-naphthalene.	1-amino-3-chlorobenzene.	Do.
Do.	1-methyl-2-amino-4-chlorobenzene.	Red.
Do.	1-trifluoromethyl-3-amino-4-chlorobenzene.	Reddish orange.
4-(6'-sulfo-2'-hydroxynaphthalene-3'-carboxylamino)-diphenyl.	1-amino-3-chlorobenzene.	Scarlet.
Do.	1,4-diethoxy-2-amino-5-benzoylaminobenzene.	Reddish black.

Red bordeaux. Yellowish scarlet. Orange. Bluish bordeaux. Yellowish red.
25 Do 2,2'-dichloro-4,4'-di-(6"-sulfo-2"-hydroxynaphthalene-3"-carboylamino)-diphenylmethane. Do 4,3'-di-(6"-sulfo-2"-hydroxynaphthalene-3"-carboylamino)-benzalnide. Do 30 1-(6"-sulfo-2"-hydroxynaphthalene-3"-carboylamino)-3-(2'-hydroxy-3'-methyl-5'-chlorobenzoylamino)-benzene. Do Do	1-amino-2-methoxy-5-chlorobenzene 1-amino-2,5-dichlorobenzene 1-amino-2-methoxy-5-chlorobenzene 1-amino-2-methyl-4-chlorobenzene 1-amino-2-methoxy-5-chlorobenzene 1-amino-2-chlorobenzene 1-amino-2,5-dichlorobenzene 1-amino-2-methoxy-4-benzoylamino-5-methyl-benzene 4,4'-dichloro-2-aminodiphenylether	Red. Yellowish scarlet. Red. Red bordeaux. Yellowish scarlet. Orange. Bluish bordeaux. Yellowish red.

35 We claim:

1. In the process of producing azo dyestuffs on mixtures consisting of wool and regenerated cellulose by combining coupling components and azo compounds on the fibers, the modification which comprises employing as coupling components 6-sulfo-2-hydroxynaphthalene-3-carboyl-arylamides the arylamide portion of which is derived from the group consisting of aromatic diamines and polycyclic monamines and applying these components from a neutral to weakly alkaline bath.
2. In the process of producing azo dyestuffs on mixtures consisting of wool and regenerated cellulose by combining coupling components and diazo compounds on the fibers, the modification which comprises employing as coupling components 6-sulfo-2-hydroxynaphthalene-3-carboyl-arylamides the arylamide portion of which is derived from aromatic diamines and applying these components from a neutral to weakly alkaline bath.
3. In the process of producing azo dyestuffs on mixtures consisting of wool and regenerated cellulose by combining coupling components and diazo compounds on the fibers, the modification which comprises employing as coupling components 6-sulfo-2-hydroxynaphthalene-3-carboyl-arylamides the arylamide portion of which is derived from bi-cyclic diamines and applying these components from a neutral to weakly alkaline bath.
4. In the process of producing azo dyestuffs on mixtures consisting of wool and regenerated cellulose by combining coupling components and diazo compounds on the fibers, the modification which comprises employing as coupling components 6-sulfo-2-hydroxynaphthalene-3-carboyl-arylamides the arylamide portion of which

is derived from bi-cyclic diamines the two nuclei being connected by one of the group consisting of the diphenyl linkage (-), -O-, -CO-, -CH₂-, -NH-, -CO.NH- and HN.CO.NH- and applying these components from a neutral to weakly alkaline bath.

5. In the process of producing azo dyestuffs on mixtures consisting of wool and regenerated cellulose by combining coupling components and diazo compounds on the fibers, the modification which comprises employing as coupling component 2,2'-dichloro-4,4'-di-(6"-sulfo-2"-hydroxynaphthalene-3"-carboylamino)-diphenyl and applying the same from a neutral to weakly alkaline bath.

6. In the process of producing azo dyestuffs on mixtures consisting of wool and regenerated cellulose by combining coupling components and diazo compounds on the fibers, the modification which comprises employing 2,2'-dichloro-4,4'-di-(6"-sulfo-2"-hydroxynaphthalene-3"-carboylamino)-diphenyl-methane and applying the same from a neutral to weakly alkaline bath.

7. Mixtures consisting of wool and regenerated cellulose dyed according to a process as claimed in claim 1.

8. Mixtures consisting of wool and regenerated cellulose dyed according to a process as claimed in claim 4.

9. Mixtures consisting of wool and regenerated cellulose dyed according to a process as claimed in claim 5.

10. Mixtures consisting of wool and regenerated cellulose dyed according to a process as claimed in claim 6.
